UNITED STATES PATENT OFFICE.

LOYD R. HENDRIX, OF SAVANNAH, GEORGIA.

DOOR-CHECK.

1,110,628.

Specification of Letters Patent. Patented Sept. 15, 1914.

Application filed May 2, 1913. Serial No. 765,070.

To all whom it may concern:

Be it known that I, Loyd R. HENDRIX, a citizen of the United States, residing at Savannah, in the county of Chatham, State of Georgia, have invented certain new and useful improvements in Door-Checks; and I do hereby declare the following to be a full, clear, and exact description of the invention, such as will enable others skilled in the art to which it appertains to make and use the same.

This invention relates to new and useful improvements in door checks, and particularly that class which is provided with resilient means for holding the same in and out of operative position.

The object of this invention resides in the provision of a door check which is provided with resilient means for holding the same in and out of engagement and which is provided with means operable by the foot for moving the check to operative position, said means being so positioned that the foot cannot come into engagement with the door to cause damage resulting in continued use of the device by the operator's foot scraping against the door when the check is operated.

A further object is to improve the general efficiency and simplicity of devices of this character.

With these and other objects and advantages in view, the invention resides in the novel combination formation and arrangement of parts more fully hereinafter described, illustrated in the accompanying drawings and particularly pointed out in the claim hereto appended.

Referring to the accompanying drawings, wherein similar characters of reference designate corresponding parts throughout the several views, and in which:

Figure 1 is a vertical sectional view showing the pawl resiliently held in inoperative position on a door. Fig. 2 is a similar view showing the pawl resiliently held in operative position to limit the movement of the door in one direction. Fig. 3 is a front elevation of the device in the position shown in Fig. 1.

Referring more particularly to the drawings, 5 designates a portion of a door having secured thereto a bracket 6 provided with laterally extending spaced parallel lugs 7

having alining openings formed in their outer ends. The floor engagement member 55 comprises a pawl 8 having preferably a pad of high friction material 9 at one end thereof. To the other end of the pawl are fastened a pair of plates 10 which extend past the said end and are provided adjacent their outer extremities with laterally and outwardly extended pintles 11 which are journaled in the openings of the lugs 7, thus providing a pivotal connection for the pawl. To provide means for resiliently holding the 65 pawl in floor engaging or raised position, a retractile spring 12 is provided, having one of its extremities secured to the body of the bracket 6 and its other extremity secured to the end of the pawl between the two plates. 70 It will be seen, that when the pawl is in raised position the force of the spring will be exerted above the pivotal point and that when the pawl is in lowered position the force of the spring will be exerted below the 75 pivotal point. By providing the plates 10, the spring is permitted to swing between the pivotal points of the device.

In order that the device may be actuated from raised to lowered position, a lug 13 is 80 provided on that face of the pawl 8 which is outermost when the pawl is in raised position. When the foot of the operator is placed on the lug to swing the pawl downwardly, it will be observed that the side of 85 the foot will only engage the adjacent face of the pawl and that therefore all danger of damaging the door by striking the foot thereagainst is obviated.

What is claimed is—

A door check comprising a vertically disposed bracket including a pair of outwardly extending parallel spaced lugs, a pawl having one end bifurcated, outwardly extending pintles on the ends of said furcations journaled in the outer ends of the lugs and a retractile spring having one end secured to the bracket and the other end secured to the pawl between the furcations.

In testimony whereof, I affix my signature, in the presence of two witnesses.

LOYD R. HENDRIX.
